UNITED STATES PATENT OFFICE

2,501,612

MECHANICAL PENCIL

Carl G. Nielsen, Racine, Wis.

Application March 16, 1946, Serial No. 654,871

1 Claim. (Cl. 120—19)

1 This invention appertains to writing and marking devices, and more particularly to a novel mechanical pencil.

One of the primary objects of my invention is to provide a simple and positive means for advancing the lead, said mechanism being of such a construction that the likelihood of the same getting out of order is reduced to a minimum.

Another salient object of my invention is to provide a lead advancing mechanism for a mechanical pencil, embodying a resilient follower or pusher rod for the lead and a thumb piece carried by the rear end of the rod normally urged into locking contact with the case of the pencil by the inherent tension of said rod for holding the lead in a set advanced position.

A further object of my invention is to provide a novel casing for the pencil which can be readily fabricated from a single sheet of material, if such is desired, and which can be so formed as to provide a guide bore for the lead and the pusher rod, a storage chamber for reserve leads and a clamp or holder for an eraser.

A further important object of my invention is to provide a mechanical pencil which is so constructed that the same can be readily made in a thin flat shape whereby the pencil can be effectively used as a book mark, letter opener, etc.; the flat shape of the pencil also giving ample flat faces for receiving engraving, advertising matter, and the like.

A still further object of my invention is to provide a practical mechanical pencil of the above character, which will be durable and efficient in use, one that will be simple and easy to manufacture, and one which can be placed upon the market at a low cost.

With these and other objects in view, the invention consists in the novel construction, arrangement and formation of parts, as will be hereinafter more specifically described, claimed, and illustrated in the accompanying drawing, in which drawing:

Figure 1 is an edge elevational view of one preferred form of my pencil.

Figure 2 is a longitudinal sectional view through the pencil.

Figure 3 is a rear end elevational view of the pencil casing, the eraser, eraser cover and lead advancing rod being shown removed.

Figure 4 is a front end elevational view of the casing for the pencil.

Figure 5 is an enlarged fragmentary detail longitudinal view through the rear end of the pencil showing a modified type of eraser which can be

associated therewith, the view being taken at right angles to Figure 2.

Referring to the drawing in detail, wherein similar reference characters designate corresponding parts throughout the several views, the letter M generally indicates my improved mechanical pencil and the same includes an elongated casing 10 preferably, but not necessarily, formed from sheet metal. This casing can be economically stamped from a single blank of sheet material and thereafter folded into shape. In the drawings, I have shown the casing constructed from a single blank of sheet metal, and this blank is folded longitudinally to provide a connecting edge wall 11 and abutting side walls 12 and 13. The edges of the blank are shaped to permit the interfitting thereof during the folding of the blank, and as illustrated in Figure 4, one edge of the blank can be provided with a longitudinally extending tongue 14 which can be received in a longitudinal groove 15 formed on the inner surface of the other edge. As is clearly shown in Figure 4, the edge carrying the groove 15 is curved over into engagement with the rib defining an edge wall 16. The forward end of the pencil casing 10 is tapered as at 17 and the adjacent faces of the walls 12 and 13 are grooved to provide a centrally extending bore or channel 18. The pencil lead 19 is slidably received in this bore or channel and the side walls 11 and 12 at the extreme forward end of the pencil are slit as at 20, and the portions of the casing on the opposite sides of the slit can be slightly pressed inwardly to provide resilient fingers 21 for gripping the lead.

At one side of the central bore or channel 18 is provided a longitudinally extending chamber 22 and extra reserve leads can be placed in this chamber. This chamber opens out through the rear end of the pencil. At the extreme rear end of the casing, the side walls 12 and 13 can be flanged outwardly to provide spaced lips 24 between which can be inserted any preferred type of an eraser. A cap 25 can be slipped over the lips 24 to house the eraser, should such be desired.

As brought out in the objects of the specification, I employ a novel lead advancing mechanism, and this lead advancing mechanism includes a resilient pusher or follower rod 26 which is slidably mounted within the bore 18 in rear of the pencil lead 19. The casing 10 itself is formed to cooperate with this advancing rod, and consequently, the wall 16 adjacent to the rear end of the pencil is cut away to expose the edges of the side walls 12 and 13, and these edges are provided

with rack teeth 27. The adjacent faces of the side walls 12 and 13 at this point are reduced in thickness to provide a slot 28 which communicates with the axial bore 18. The inner or rear end of the resilient follower rod 26 has formed thereon an outwardly extending operating arm 29 which extends through this slot, and this arm has connected therewith a thumb piece 30. The inner face of the thumb piece has formed thereon teeth 31 which mate with the teeth of the rack bars 27. The inherent tension of the rod 26 normally holds the teeth of the thumb piece 30 into engagement with the rack bar so that the rod 27 will be held in a set position.

When it is desired to advance the lead 19, the thumb piece 30 can be forcibly slid over the rack teeth or the thumb piece 30 can be grasped in the fingers and pulled outwardly away from the racks 27, after which the rod can be pushed forward.

In lieu of slidably mounting an eraser between the flanges or lips 24 and providing an extraneous cover 25 for the eraser, I can utilize an eraser 32 (see Figure 5) held in a holder 33. The holder 33 can be detachably mounted between the flanges or lips 24 and when the eraser is not in use, the holder and the eraser can have its position reversed so that the eraser will be positioned between the flanges or lips with the holder 33 extending outwardly. The holder in this position 30 will form a finishing piece for the case.

While I have shown the pencil casing formed flat, so as to provide a thin pencil, obviously, the casing can be made in other shapes.

However, it is preferred to make the casing 35 shown, as this provides a thin flat pencil which can be used as a book mark, letter opener, or the like.

It is also obvious that I can provide two or more bores 18 with lead advancing mechanism in each bore so that a plurality of writing points will be had for different colored leads.

Changes in details can be made without departing from the spirit or the scope of my invention, but what I claim as new is:

A mechanical pencil comprising a casing having a longitudinal lead receiving bore, a resilient pusher rod for the lead slidably mounted in said bore, said casing being provided with a slot communicating with the bore and ratchet teeth at least on one side of the slot, a laterally extending arm on the inner end of the rod extending through the slot, and a finger piece secured to said arm and movable with the arm and rod as a unit having teeth for engaging the rack bar, the inherent resiliency of the rod holding the teeth of the finger piece in engagement with the rack bar.
